CLAIM

The ornamental design for a double cat bed, as shown and described.

DESCRIPTION

FIG. 1 is a front perspective view of a double cat bed, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view of the double cat bed of FIG. 1 in a configuration with the frame and platforms shown separately to reveal all aspects of the design.

The broken lines in the drawings illustrate the portions of the double cat bed, which form no part of the claimed design.
